PAUL GUILBERT, OF ROUEN, AND JULES LEGRAND, OF ST. MANDE, FRANCE

PLANT FOR LOADING AND UNLOADING WAGONS

Application filed September 12, 1930, Serial No. 481,534, and in France December 10, 1929.

Railway companies are always greatly concerned with the keeping clean of their ballast, which is the chief condition for the proper upkeep of railroad tracks.

When it is desired to have constantly clean ballast without being compelled to renew it completely which would be very costly, the old ballast is sifted so as to remove the earthy material and the minute particles produced by the crushing of the stones. Thus only those stones are retained the size of which is above that of the screen mesh chosen. The volume of ballast is completed by adding a certain amount of fresh ballast.

This manner of regenerating the ballast is much cheaper than its simple replacement and consequently it is much used nowadays. It used to be effected entirely by hand, but lately it has been executed mechanically by machines having a very large output. The sifting however is subject to a very hindrance trouble which consists in the necessity of removing the waste falling on the sides of the track during the operation of ballast-regeneration. Heretofore such waste had to be loaded on a service train passing in front of the yard on the moments available between the passages of the regular trains, the loading of the waste being effected with shovels. This work is lengthy and requires the formation of a special service train the efficiency of which is very small and which moreover may be a cause of disturbance for the ordinary trains.

The mechanical sifting methods which increase the speed of progress of the yards along the railroad track have simultaneously increased the volume of waste to be removed whereby the operation has become more and more difficult.

Our invention has for its object to remove this drawback by means of a mechanical arrangement for loading waste from sifting operations into ballast-trucks comprising means for the speedy unloading thereof.

Appended drawings show by way of example two forms of execution of our invention supposed used in combination with a high efficiency ballast-removing vehicle provided or not with sifting means.

In appended drawings:

Fig. 1 is a side view of a part of the whole arrangement.

Fig. 1A is a similar view and a continuation of Fig. 1. 55

Fig. 2 is an end view thereof.

Fig. 3 is a side view showing the truck-unloading means in operation.

Fig. 4 is an end view thereof.

Figs. 5 and 6 are respectively a side view 60 and an end view of a modification of said means.

Referring to Figs. 1 and 2, the waste produced by the sifting operation are raised by the conveyor *a* from the ballast removing vehicle and fall into a hopper *b* carried by the frame *d* supported by the truck *c*. To the longitudinal sides of the truck are secured two rails *e*—*e* on which a carriage *f* carrying a hopper *g* is adapted to run. This carriage *f* is self propelling through the agency of a motor *h* and of suitable transmissions. It may run over the rails *e*—*e* not only on the truck *c* but also on the adjacent truck *z* and the following trucks which are all provided with the same rail arrangement along their sides, the rails forming a continuous track from one end of the train to the other owing to the interposition of a pivoted link arrangement between each two successive trucks. 70

The arrangement comprising the hoppers, carriages and rails therefor is adapted to pass inside the gauge *y* of goods-carriage for the track along which the trucks move.

The working is as follows:

The hopper *b* being full, its bottom *l* is opened and the contents fall into the hopper *g*. The bottom *l* is then closed again, the carriage *f* is caused to start so as to bring the hopper *g* to point *g*¹ for instance on the following truck *z*. There its bottom *m* is opened and its contents fall into the ballast-truck *z* after which the hopper *g* is returned with its carriage *f* underneath the hopper *b* which has been filled again during the transportation, unloading and return of the hopper *g*. Its bottom *l* is again opened and operations begin over again whereby it is possible to fill in successively all the trucks disposed behind one another. 100

This arrangement may be provided to the rear of a ballast-distributing truck provided or not with sifting means, the working being obviously similar in both cases. It may be used also for removing clay from the track platform or for making it deeper and generally speaking in all cases where material of any kind produced for instance by earthwork or the like is to be removed and loaded on trucks disposed on or moving along the railroad.

After such material has been loaded as explained on trucks such as z through the agency of the above described loading system, the trucks have to be emptied. In ordinary earthwork yards, the problem of unloading earth or material loaded on trucks is generally solved either by unloading the trucks with shovels or by using tipping wagons. Self unloading hopper cars which are of interest in certain particular cases are not adapted for unloading earth in embanking because their contents fall too near the track. As, on the other hand, it is difficult to provide tipping means for large-sized standard gauge trucks, it is necessary in most cases to unload the trucks with shovels which is obviously costly and immobilizes a considerable number of trucks owing to the length of operation.

The unloading is particularly difficult in the case of ballast trucks with high rims and when it is desired to unload the material at any point of the railroad which is the case for instance for the waste from ballast-sifting which waste is generally thrown out on the embankment near the place of sifting so as to avoid any long transportation.

These drawbacks which would considerably reduce the interest of the direct loading arrangement which is one of the features of our invention as described may be removed by the unloading means which form a complementary feature thereof.

Referring to Figs. 3 and 4, these unloading means are carried by a frame j running over the rails e secured to the sides of the tracks as explained hereinabove whereby said frame may pass from one truck to the next. Thus only one frame is required for the whole train of similarly equipped trucks.

The frame j carries an arrangement of chains o and buckets carried by a pivoting support k held through the crane w and the cables w_1 . The support may be raised into the position k higher than the truck rim when the frame is to pass from one truck on to the next.

The chains o are driven from a shaft p to which are keyed central bosses p_1 similar to those used on excavators. In the machine illustrated, there are three chains used carrying two sets of buckets r r_1 adapted to remove the material throughout the width of the truck. Of course, the number of chains

and sets of buckets may be chosen as desired. For instance they may be provided only with one set of buckets the width of which is equal to or smaller than that of the truck; the buckets being adapted in this latter case to sweep the whole width of the truck through a pivoting or a transversal motion.

The buckets rotating in the direction of the arrow are filled as they pass through the material and unload into the hopper s over the band conveyor s' , which runs transversally with reference to the track and moves with a speed sufficient for projecting the material on to the desired spot.

All the movements of the arrangement such as the control of the bucket conveyor, the raising of its pivoting support, the control of the transverse conveyor, the progress of the carriage are obtained through one or more motors of any description of the gasoline, electric or any other type, the control being effected through a plurality of parts acted upon by the machinist.

The whole arrangement is such that it passes entirely inside the gauge of goods carriage y for the track on which the truck runs.

Under such conditions the train arriving at the point where the earth or the like is to be unloaded, the pivoting support being in its position k , the apparatus is started. The buckets are filled as they pass through u and empty their contents over the conveyor s , which projects the material at the desired point u_1 . The automatic advance motion of the frame j in the direction n ensures an excellent filling of the buckets. When the frame arrives over point q the truck is empty. The pivoting support is raised into its position k_1 and the frame j is moved over the next truck z , where operation is resumed.

Figs. 5 and 6 illustrate a modification of this device. Instead of using buckets digging after the manner of excavators, we may use as shown buckets x , earthing up as in the case of dredges or shovel machines. The direction of motion of the bucket chain is reversed in this case, the progress of the frame j being effected in the direction of the arrow t . The pivoting support v of the bucket chain x may likewise be raised into v_1 for passing the frame from one truck to the other.

In the example shown the device comprises two series of buckets but it may as well comprise more or else only one the width of which is smaller than that of the truck the whole width of which is swept in this case owing to a transversal motion of the bucket chain.

In the last modification shown, all the movements are controlled mechanically.

Our invention covers also the method of working corresponding to the use of the above described truck equipments.

What we claim is:

1. A truck equipment for the handling of waste produced by ballast-screening or the like comprising a truck, a hopper secured over same, a movable bottom for said hopper, means for loading the hopper, rails carried along the sides of the truck, a carriage adapted to run over said rails, a second hopper carried by said carriage and adapted to pass underneath the first hopper, a removable bottom for the second hopper and means for unloading the truck.

5 2. A truck equipment for the handling of waste produced by ballast screening or the like comprising a series of successive trucks, a hopper secured over one of said trucks, a movable bottom for said hopper, means for loading the hopper, rails carried along the sides of the trucks, a carriage adapted to run over said rails, a second hopper carried by said carriage and adapted to pass underneath the first hopper, a removable bottom for the second hopper, means between the rails of the successive trucks whereby the carriage may pass thereover, and means for unloading the trucks.

10 3. A truck equipment for the handling of waste produced by ballast screening or the like comprising, a series of successive trucks, a hopper secured over one of said trucks, a movable bottom for said hopper, means for loading the hopper, rails carried along the sides of the trucks, a carriage adapted to run over said rails, a second hopper carried by said carriage and adapted to pass underneath the first hopper, a removable bottom for the second hopper, a pivoted link between the rails of the successive trucks and movable to a position for interconnecting said rails of the successive trucks whereby the carriage may pass thereover, and means for unloading the trucks.

15 In witness whereof we have hereunto set our hands.

45 PAUL GUILBERT.
JULES LEGRAND.
